7254X

Henry King

Letter of Patent.

The vehicle referred to in those Letters Patent, and making part of the same, containing a description in the words of the applicant Henry King himself of his improvement in the Hack wrench.

It is composed of a handle of hard wood or any other hard material into which a square bar of iron, ^{flat} is riveted upon the other end of said bar is a hammer upon the upper side of this bar is a ratchet into which a click is forced by a spring which moves upon a pivot in a slide which slides upon the bar inwards toward the movement of the slide towards the handle & pressing its situation & also to regulate the distance between one end of the slide & the hammer which taken together form the claws of the wrench.

The slide is composed of three parts, one of which is a jaw of the wrench, another part is an upright piece to which the click and spring are attached, these two uprights are connected together by a piece of iron (the same thickness as the main bar) and riveted firmly at each end.... The slide is made to move upon the bar by the bars passing thro' it in such a manner that it cannot be detached.... The machine being placed upon a flat or bar no other slide moved up, it will be held firm by the click passing into the ratchet, it will then be evident that by taking hold of the handle and moving it, it will turn the nut or bar....

The applicant claims nothing in relation to the use of the ratchet and click.
